(57) **CLAIM**

The ornamental design for a fire hydrant-shaped bottle opener, as shown and described.

DESCRIPTION

FIG. 1 is an isometric view of the fire hydrant-shaped bottle opener of the present invention;

FIG. 2 is a front view of the fire hydrant-shaped bottle opener of FIG. 1;

FIG. 3 is a side view of the fire hydrant-shaped bottle opener of FIG. 1, as seen from the left side of FIG. 2, the right side being a mirror image thereof;

FIG. 4 is a rear view of the fire hydrant-shaped bottle opener of FIG. 1; and,

FIG. 5 is a top plan view of the fire hydrant-shaped bottle opener of FIG. 1.

1 Claim, 3 Drawing SheetsFIG. 1
